UNITED STATES PATENT OFFICE.

WILLIAM B. STOUT, OF DETROIT, MICHIGAN.

TOY.

Application filed February 3, 1923. Serial No. 616,637.

The present invention relates to toys, and is especially directed to improvements in toys of the so-called trundling or pusher type.

5 The general object of the present invention is to provide a toy of the aforesaid type which will afford amusement to the young and may also be used by adults in contests of skill or in the playing of games.

10 More specifically, it is the object of this invention to provide a trundling or pusher toy which may be economically produced and which is so constructed that certain movements may be imparted to the essential 15 element or figure thereof which will simulate the movements of the object which such element or figure represents or resembles.

Other objects and advantages of my invention will present themselves as the description proceeds, and I would have it understood that I reserve unto myself all rights to the full range of equivalents, both in structure and uses, to which I may be entitled under my invention in its broadest 25 aspect, as defined by the appended claims.

For the purposes of the present disclosure, I have elected to illustrate and describe a preferred embodiment of my invention, but it will be obvious that the invention may 30 take other forms without departing from the spirit and scope thereof.

In the drawings, Figure 1 is a side elevation of a trundling or pusher toy made in accordance with my invention; and Figure 35 2 is a transverse section on the line 2--2 of Fig. 1.

Referring now to the drawings in detail, in which like characters of reference are employed to designate similar parts in the 40 several views, 7 indicates a disk-wheel or roller which may be made of wood, cardboard or any other suitable material, which is revolubly mounted on the lower end of the bracket 8 carried by and offset from the 45 rod or stick 9. In mounting the said disk-wheel 7 on said bracket, any suitable form of axle may be employed; but I have found a simple mounting may be provided by means of a bolt 10 passing through a central 50 aperture in the disk-wheel 7 and the bearing in the lower end of the bracket 8. A suitable spacing nut 10^a may be interposed between the opposed faces of the disk-wheel 7 and the bracket 8, so that the wheel 7 will be maintained in properly spaced 55 relation from the bracket to insure freedom of

rotation. A securing-nut 10^b is threaded on to the protruding end of the bolt 10 to maintain the elements 7 and 8 in assembled relation. 60

In the present showing of my invention, the essential element or figure of the toy is the representation of a donkey indicated at 11. This figure may be made of any material suitable to the purpose, but is preferably 65 cut from a block of wood, as by a jig-saw. The hind legs 11^a and fore legs 11^b, as will be clearly seen from Fig. 2, are immovably fastened or secured to the opposite sides of the body portion of the figure 11. It will 70 be noted that the legs 11^a and 11^b of the figure 11 are extended rearwardly and forwardly, and are so shaped as to conform substantially to the position which would be taken by the legs of the animal represented when moving at a gallop. 75

The hind legs 11^a are eccentrically connected to the disk-wheel 7 by means of a screw or bolt 12, as shown in Fig. 2. This screw or bolt 12 is positioned within the 80 aligned apertures of the hoofs 11^c of the hind legs 11, and extends through a hole in the wheel 7. A spacing or lock-nut 12^a may be interposed between the opposed surfaces of the wheel 7 and the innermost hind leg 85 11^a, the end of the screw or bolt 12 being held in place within the hole in the wheel 7 by means of a nut 12^b.

It will be apparent from the description thus far given that, as the wheel 7 rotates 90 on its axis, the eccentric mounting of the hind legs of the figure 11 will impart an oscillatory movement to said figure, and, in order that the functioning of the toy may not be impaired by the fore legs coming in 95 contact with the ground, possibly resulting in their breakage by striking obstructions, I have provided a means of connection between the body portion of the figure 11 and the shaft or stick 9 to limit the range of 100 oscillatory movement of the figure. This connection is made by means of the tail 11^d of the donkey which is pivotally connected at one end to the body portion of the figure 11 and at its opposite end to the 105 shaft or stick 9. In the present embodiment of my invention, I have shown a simple method of connecting the tail 11^d to the body portion of figure 11, which comprises a pin 13 which is adapted to be driven into 110 the body 11 and is provided with an angular portion 13^a on which the tail 11^d is rotat-

ably supported. The other end of the tail 11^d is apertured to receive a screw 14 adapted for seating in the shaft or rod 9. The relative range of movement imparted to the figure of the donkey by the revolution of the wheel 7 is clearly shown by the full and dotted lines of Fig. 1. In this connection, it may be observed that the tail 11^d, when the connection between the wheel 7 and the hind legs 11^a of the donkey is at bottom center, serves to maintain the fore feet of the donkey out of contact with the ground or surface on which the toy is being operated, while, when the eccentric connection is at top center, the body of the donkey will be given a considerable upward inclination, so that the rapid movement of the toy will produce a motion in the figure of the donkey which will closely resemble the galloping movements of that animal.

The figure of the donkey may be embellished with any suitable decorations, and is preferably provided with the representation of a saddle to indicate the point of location 25 of the rider or jockey 15. The jockey or rider 15 is preferably formed from a block of wood, similar to the figure of the donkey, the legs 15^a and 15^b being spaced apart and preferably immovably fastened to the opposite sides of the body portion of the said figure 15 and adjacent to the lower end thereof. The lower edge of the body portion of the rider or jockey 15 may be shaped to conform to the contour of the upper edge 35 of the body portion of the donkey 11, so that the jockey or rider 15 may have a relatively firm seat on the donkey's back when positioned astride thereof, as shown in Fig. 2. The jockey or rider 15 is removably 40 mounted on the back of the donkey, being held in position thereon by its own inertia. Consequently, it will be manifest that, in the operation or use of the toy, the rapid movement or oscillation of the donkey will 45 have a tendency to unseat the jockey or rider, thereby adding considerably to the amusement afforded by the motion of the donkey. Furthermore, it will be evident that, by 50 loosely mounting the jockey or rider on the donkey's back, trials of skill may be indulged in with my invention, having as an ultimate object the operation of the toy at a high speed without unseating the rider.

I claim:

55 1. A trundling toy having a shaft, a wheel revolvably mounted thereon, a device comprising single rigid structure representing an animal figure, said figure including a body and forward and rearward extensions such as legs, an eccentrically disposed pivotal connection between one of said rearward extensions and the shaft of said wheel, and

65 a single-link pivotal connection between said shaft and another part of said single rigid structure.

2. A trundling toy having a shaft, a wheel revolvably mounted thereon, a device comprising an animal figure representing a quadruped having a switchable tail, said device having a body and rigid rearward extensions such as legs, an eccentrically disposed pivotal connection between one of said rearward extensions and the shaft of said wheel, and a member simulating said tail and pivotally connected at one end to said body and at its other end to said shaft.

70 3. A trundling toy having a shaft, a wheel revolvably mounted thereon, a device comprising a single rigid structure representing an animal figure, said figure including a body and forward and rearward extensions such as legs, an eccentrically disposed pivotal connection between said wheel and one of said rearward extensions near the end thereof, and a link-connection means between said shaft and a point on the body, the parts being so shaped and connected that on 75 trundling the toy with the shaft held inclined to the horizontal the animal figure has an alternate rising and falling movement with its major portion always ahead of the wheel.

80 4. A trundling toy having a shaft, a wheel revolvably mounted thereon, a device comprising a single rigid structure representing an animal figure, said figure including a body and forward and rearward extensions such as legs, an eccentrically disposed pivotal connection between said wheel and one of said rearward extensions near the end thereof, and a link-connection means between 85 said shaft and a point on the body, the shaft being straight from its lower end to at least above the point where the means last mentioned is connected to the shaft, and the parts being so shaped and connected that on trundling the toy the animal figure once during each revolution of the wheel 90 "rears up" to dispose the mid portion of its "back" at a comparatively sharp rearward and downward inclination; said toy also including a figure simulating a rider of the animal and having a bifurcated lower portion for straddling said "back" portion of the animal figure, said rider figure being disconnected from the animal figure except by 95 gravity and friction, said rider being in insecure stable equilibrium upon said animal, whereby that the maintenance of its "seat" by the rider figure is dependent on the skill 100 of the person handling the device while rolling the wheel at a certain speed.

105 WILLIAM B. STOUT.
